UNITED STATES PATENT OFFICE.

EDGAR D. HUME, OF COLLINGSWOOD, NEW JERSEY, ASSIGNOR TO SUMMIT THREAD COMPANY, OF EAST HAMPTON, CONNECTICUT, A CORPORATION OF MAINE.

BOBBIN CASE FOR SEWING-MACHINE SHUTTLES.

Application filed June 10, 1922. Serial No. 567,276.

To all whom it may concern:

Be it known that I, EDGAR D. HUME, a citizen of the United States, residing at Collingswood, in the county of Camden and State of New Jersey, have invented new and useful Improvements in Bobbin Cases for Sewing-Machine Shuttles, of which the following is a specification.

This invention relates to a circular bobbin case used with a rotary shuttle, and having a central post on which a bobbin is rotatable, the case being composed of a base carrying the post, and a cap, the top of which is centrally apertured to receive the outer end of the post, and formed to engage a spring-pressed latch pivoted to the post, and adapted to detachably secure the cap to the base.

A bobbin on the post is yieldingly pressed outward from the base by spring means provided for that purpose, and the outer end of the bobbin is held by said means in yielding contact with the top portion of the cap. Said portion has an inwardly projecting annular boss surrounding the post-receiving aperture, and forming an annular depression in the cap, adapted to receive the latch. Heretofore, the boss has constituted the portion against which the outer end of the bobbin is pressed. The outer end of the bobbin is spaced by said boss from the dished portion of the top or head portion of the cap surrounding the boss.

Thread unwound from the bobbin is liable to enter said space and be caught between the bobbin and the cap top, the bobbin being yieldingly pressed toward the cap top, as above stated. This constitutes an objection to bobbin cases characterized as described, of which there are many in use at the present time particularly in the Singer post machine, employing the bobbin case of the well known Wheeler & Wilson type. Moreover, it is not feasible to employ in a case of this type a ready wound bobbin composed of a cop tube or core formed to loosely receive the post, and a winding of thread on the core, the thread being universally wound, so that the ends, as well as the periphery of the winding, are exposed, thread leaving the outer end of the winding being particularly liable to be caught between the bobbin and the top of the cap.

One object of the invention is to obviate the objection above stated, and enable a

ready wound bobbin to be advantageously used with a bobbin case of the type described.

Another object is to provide an improved form of means for pressing the bobbin toward the cap top, whereby the inner end of the bobbin is covered and guarded so that thread cannot drop therefrom into the space between the inner end of the bobbin and the body of the base.

In attaining these results I combine with a bobbin case characterized as above described, an inner or supplemental head or adapter, adapted to be conveniently fixed to the cap, in position to bear on the entire outer end of a ready wound bobbin, and to overhang the margin of the thread winding, so that thread cannot rise from the outer end of the winding, and the entrance of loose thread from the periphery of the winding into the space between the outer end of the winding and the top or head portion of the cap is impossible.

I also provide as an element of the means whereby the bobbin is pressed outward, a disk of greater diameter than the bobbin, and adapted to guard the inner end of the latter.

Of the accompanying drawings forming a part of this specification,—

Figure 1 is a top plan view of a bobbin case of the type to which my improvement is applicable.

Figure 2 is a section on line 2—2 of Figure 1.

Figure 3 is a sectional view of the cap.

Figure 4 is a sectional view of the base.

Figure 5 is a section on line 5—5 of Figure 3.

Figure 6 is a perspective view of the inner or supplemental head.

Figure 7 is a perspective view of a ready wound bobbin.

Figure 8 is a perspective view of the spring-pressed plate which bears on the inner end of the bobbin.

Figure 9 is a perspective view of the adjustable stop.

The same reference characters indicate the same parts in all of the figures.

12 represents the circular body portion, and 13 the annular wall portion of the base of a bobbin case of the type to which my invention relates. A central post 14 is fixed to the body 13, and to its outer end is pivoted

a latch 15, adapted to be held by spring pressure in the positions shown by Figures 2 and 4. 16 represents the circular head portion, and 17 the annular wall portion of the cap. 5 The head portion has a central aperture 18, and an annular latch-receiving depression 19, formed by an inwardly projecting annular boss 20, surrounding the aperture. The base and cap form a bobbin chamber surrounding the post.

The case is provided with means for supporting the inner end of a bobbin within the chamber, and pressing the bobbin outward toward the cap head and top 16, said means 15 being embodied in a flat disk 21, having a central aperture 22, loose-surrounding the post 14, and a crowning volute spring 23, seated on the base and supporting the disk. The diameter of the disk 21 is slightly less 20 than the internal diameter of the wall portions 13 and 17, so that the disk is freely movable sidewise in the bobbin chamber. Outward movement of the disk is limited by 25 a stop on the post, formed, in this instance, by a split sleeve 24, of resilient sheet metal, adapted to hug the post and be frictionally retained thereon against accidental endwise movement.

The disk 21 is adapted to support a ready 30 wound bobbin, composed of a paper tube or core 25, and a winding 26 of thread, the diameter of the disk being preferably greater than the maximum diameter of the bobbin, and so nearly equal to the diameter of the 35 bobbin chamber that there is not room for loose thread to drop through the annular crevice between the disk and the bobbin chamber wall, so that entrance of the thread into the space between the inner end of the 40 bobbin and the body 12 of the base is prevented.

With the bobbin case and the spring-pressed bobbin-supporting disk above described, I combine an inner head 28, which 45 prevents loose thread from entering the space between the outer end of the bobbin and the cap head or top 16. Said inner head is a flat-sided disk of slightly larger diameter than the disk 21. The cap head 16 is 50 somewhat crowning at its marginal portion, and joins the wall portion 17 at an obtuse angle. The diameter of the inner head is such that its margin is adapted to have a close frictional fit on the inner surface of 55 the wall portion 17, so that when the inner head is pressed against the angle at the junction of the head 16, and wall portion 17, it is tightly wedged in place, and constitutes a practically inseparable part of the cap.

60 An aperture 29 in the center of the inner head receives the outer end of the post 14, as shown by Figures 1 and 2.

When a bobbin is deposited on the disk 21, and the cap is placed on the base, and 65 secured by the latch, the outer end of the

bobbin is pressed by the force of the spring 23 against the inner head 28, which covers all portions of the outer end of the bobbin, and overhangs the periphery of the latter, so that loose thread is prevented from entering the space between the outer end of the bobbin and the cap head 16.

It will now be seen that the bobbin is guarded at both ends, so that thread can 70 pass from the bobbin only through the usual orifices provided for the passage of the thread to the tension devices on the exterior of the wall portion 17.

It will also be seen that the inner head 28 constitutes a simple and easily applied adapter, which enables the cap to guard the outer end of a ready wound bobbin, the fact being, that without the inner head, the recessed and embossed cap head 16 can be used only with a bobbin including a spool with deep flanges between which the thread must be wound from time to time by the operator, one of said flanges bearing on the boss 20. The inner head 28 constitutes a frictional bearing for the entire surface of the outer 90 end of the bobbin preventing undesirably loose rotation of the latter. The spring-pressed disk 21 constitutes a similar frictional bearing which, by reason of the fact that its diameter is greater than that of the 95 bobbin, aids in preventing loose rotation of the bobbin.

The stop sleeve 24 is adjustable longitudinally on the post, so that the minimum space 100 between the disk 21 and the inner head 28 may be varied, according to the length of the bobbin.

I claim:

1. A bobbin case comprising a base composed of a circular body and an annular wall portion; a central post fixed to the base body; a latch pivoted to the post; and a cap composed of an annular wall portion and a head which is apertured to receive the outer end of the post, and is provided with an annular inwardly projecting boss forming a latch-receiving depression, the said base and cap forming a chamber in which a bobbin is rotatable on the post; combined with a flat-sided discoidal inner head frictionally engaged with the annular wall portion of the cap, in position to bear on and guard the outer end of a ready wound bobbin, said inner head having a central post-receiving aperture and being of such diameter that it overhangs the periphery of the bobbin; and means for pressing the bobbin against the inner head.

2. A bobbin case embodying the combination specified by claim 1, said pressing means being embodied in a spring-pressed disk movable in the bobbin chamber, and provided with a central post-receiving aperture, the diameter of the disk being such that it is adapted to contact with and guard

- the inner end of the bobbin throughout the entire area of said end.
3. A bobbin case embodying the combination specified by claim 1, said pressing means being embodied in a spring-pressed disk movable in the bobbin chamber, and provided with a central post-receiving aperture, the diameter of the disk being such that it is adapted to contact with and guard the inner end of the bobbin throughout the entire area of said end, the said post being provided with an adjustable stop adapted to vary the minimum distance between said disk and the said inner head.
- 15 4. A bobbin case comprising a base having a circular body and an annular wall portion, a central post fixed to the base

body, a cap having an annular wall portion and a head apertured to receive the outer end of the post, means for securing the cap in position on the post, two parallel flat disks apertured to receive the post and each of a diameter as great as that of the largest bobbin adapted to be used in the case, said disks being respectively fitted about the post within the base body and supported within the cap, a spring arranged about the post between the base body and the adjacent disk, and an adjustable stop on the post for limiting movement of the last said disk by the spring.

In testimony whereof I have affixed my signature.

EDGAR D. HUME.
